US00D654865S

(12) **United States Design Patent**
DuMelle et al.

(10) **Patent No.:** **US D654,865 S**
(45) **Date of Patent:** **** Feb. 28, 2012**

(54) **JUMP STARTER**

(75) Inventors: **Barbara M. DuMelle**, Niles, IL (US); **Christopher M. Kubik**, Chicago, IL (US); **Patrick J. Clarke**, St. Charles, IL (US); **Samuel Weisbard**, Highland Park, IL (US); **Joseph J. Zenkus**, Lake in the Hills, IL (US); **Mark Kurth**, Chicago, IL (US); **Timothy Payne**, Chicago, IL (US); **Adam Callif**, Chicago, IL (US)

(73) Assignee: **Schumacher Electric Corporation**, Mt. Prospect, IL (US)

(**) Term: **14 Years**

(21) Appl. No.: **29/397,730**

(22) Filed: **Jul. 20, 2011**

(57) **CLAIM**

The ornamental design for a jump starter, as shown and described.

DESCRIPTION

FIG. 1 is a front isometric view of a jump starter in accordance with the present invention.

FIG. 2 is a rear isometric view of the jump starter illustrated in FIG. 1.

FIG. 3 is a bottom plan view of the jump starter illustrated in FIG. 1.

FIG. 4 is a front elevation view of the jump starter illustrated in FIG. 1.

FIG. 5 is a left side elevation view of the jump starter illustrated in FIG. 1.

FIG. 6 is a rear elevation view of the jump starter illustrated in FIG. 1; and,

FIG. 7 is a top plan view of the jump starter illustrated in FIG. 1.

The broken lines shown in the drawings are included for the purpose of illustrating environmental structure and form no part of the claimed design.

1 Claim, 4 Drawing Sheets
